COMPRESSOR

Charles Schaer, Langenthal, Switzerland, assignor to Sulzer Frères, Société Anonyme, Winterthur, Switzerland

Application January 9, 1934, Serial No. 705,907
In Switzerland January 14, 1933

19 Claims.

(Cl. 230—21)

This invention relates to a compressor. In the form shown herewith it is applied particularly to a piston compressor.

It has for one object to provide in connection with a compressor a variable clearance. Another object is to provide in connection with a compressor a plurality of variable clearances. A further object is to provide in connection with a compressor, having a plurality of variable clearances, unitary means for controlling all of said clearances and for controlling the movement of said unitary means in response to a variable factor of the compressor system. A further object of the invention is to provide such a variable clearance system in a multi-stage compressor. Another object of the invention is to provide automatic control means in a form suitable for use under the conditions existing in a refrigerating system and also under the different conditions existing in compressed air power drives.

In the form of the invention here illustrated, a piston is arranged to control a primary variable clearance directly by its own movement, and to control additional clearances also by its own movement, so that the movement of the piston directly provides a variable clearance and also controls the access to one or more additional clearance spaces. The movement of this piston is controlled in accordance with a variable factor which varies with the operation of the system. This may, for example, be the pressure at the intake or the discharge, or it may be any other desired variable factor which varies with the operation of the compressor system.

Other objects will appear from time to time in the specification and claims.

The invention is illustrated more or less diagrammatically in the accompanying drawings, wherein:

Figure 1 is a diagrammatic sectional view showing a portion of the compressor and the control mechanism;

Figure 2 is a transverse section, taken at line II—II of Figure 1;

Figure 3 is a side view of the compressor; and

Figure 4 is a sectional view generally similar to Figure 1, showing a modified form of the invention.

Like parts are designated by like characters throughout the specification and drawings.

The cylinder may be of any suitable design. Its particular details, including intake and discharge means, supply of driving fluid for the servo-motor and detailed connections, are not

fully illustrated in Figure 1. As shown in Figure 1, A is a double-walled cylinder. A¹ is a piston mounted within the cylinder for reciprocation.

B is a housing member provided with a portion B¹ of reduced diameter which fits into the cylinder A and serves as a cylinder head. A laterally extending flange B², formed on the housing B, rests upon the cylinder A and serves as a means of attaching the housing to the cylinder. The housing B is shaped to provide a small cylinder B³, which, at its upper end, is enlarged as at B⁴ to provide a double acting servo-motor cylinder. The walls of the cylinder B³ are provided with perforations B⁵, B⁶ and B⁷. As shown in Figure 1, these perforations or ports are situated at different levels, one above the other. They communicate with clearance spaces B⁸, B⁹ and B¹⁰, respectively, which clearance spaces are formed within the housing B and are separated from each other by partition members, as shown in Figure 2. There are thus formed within the housing B, and particularly within the reduced section B¹, three separate clearance spaces, each of which may be in communication with the cylinder B³ through its respective ports B⁵, B⁶ or B⁷.

C is a piston mounted to reciprocate within the cylinder B³. At its upper end it is provided with an enlarged piston C¹ mounted to reciprocate within the enlarged cylinder portion B⁴. The piston C¹ acts as a servo-motor in a manner which will be described below. There is thus provided within the cylinder B⁴ a working space C², beneath the piston C¹, and a working space C³, above it. At its upper end the piston C¹ is provided with a rod C⁴ which extends through the partition member C⁵ within the housing B. This partition member serves to separate the clearance spaces B⁸, B⁹ and B¹⁰ from the remainder of the interior of the housing. A stuffing box C⁶ prevents leakage from the working space C³. C⁷ is a pipe carrying a pressure fluid from any desired source. C⁸ is a pipe joined to the pipe C⁷ and communicating with the working space C². It may be provided with a throttling member C⁹. At its upper end, and beyond the pipe C⁸, the pipe C⁷ communicates with the working space C³ and it may also be provided with a throttling member C¹⁰.

D is a pipe, at one end in communication with the working space C² and at the other end in communication with the annular space D¹, formed within the part D², which itself lies within the housing B. The annular space D¹

is preferably continuous about the interior of the member D^2 . D^3 is a pipe, at one end communicating with the working space C^3 and at the other end communicating with an annular space D^4 about the interior of the member D^2 . The member D^2 is hollow as shown. It is provided with the two annular spaces D^1 and D^4 about its inner bore. D^5 is a hollow slide valve mounted within the member D^2 and provided with ports D^6 and D^7 . D^8 is a second hollow slide valve mounted within the member D^2 and about the first mentioned slide valve D^5 . It is provided with ports D^9 and D^{10} . It will be noticed that the ports D^6 and D^7 are spaced closer together with respect to the length of the slide valve D^5 than the ports D^9 and D^{10} , and thus only two of them can be in communication at one time. At its lower end the slide valve D^8 is connected to a lever D^{11} . This lever is pivoted at D^{12} and at its other end is connected to the rod C^4 of the piston C^1 . At its upper end the hollow slide valve D^5 is connected to a lever D^{13} . This lever is pivoted at D^{14} , and at D^{15} is slidably connected to the member D^{16} which is attached to the pressure-responsive member D^{17} . The spring D^{18} is mounted within this member and at one end contacts the end of the member D^{17} and at the other end contacts an adjustable abutment member D^{19} , which may be attached to a screw D^{20} . The screw may be moved in and out to adjust the position of the member D^{19} and to vary the compression of the spring D^{18} . D^{21} is an opening, preferably to the atmosphere, so arranged that the interior of the member D^{17} is under constant pressure. D^{22} is the space within the member D^{17} .

The upper portion of the housing B defines a space E , which is above the partition member C^5 , and it is within this chamber E that the cut-off valves D^5 and D^8 are mounted to move. Leading from the chamber E to some point within the system which is affected by the variation in the intake suction of the compressor, is a pipe E^1 . The pipe E^1 might lead to a point affected by the discharge pressure.

In Figure 3 the cylinder A has a suction pipe A^2 , the suction valve A^3 , the discharge valve A^4 and the discharge pipe A^5 . From the suction pipe A^2 the pressure-equalizing pipe A^6 leads to the crankcase A^7 , which is consequently subjected to the suction pressure of the compressor. From the housing B the pipe E^1 leads to crankcase A^7 . The gear-wheel pump C^{11} , which is driven from the crankshaft of the compressor, draws the driving fluid from the crankcase A^7 and delivers it into the pipe C^7 .

The form of the invention shown in Figure 4 differs from that shown in Figure 1, mainly in the fact that compression is accomplished in two stages and that instead of the single piston A^1 of Figure 1, a two-stage piston is provided. Thus in the form of the invention shown in Figure 4, there is a piston F which is provided with an enlarged portion F^1 . F^2 is the cylinder within which the piston is mounted for reciprocation. As shown, it is of two diameters, the smaller suitable for the piston portion F and the larger suitable for the piston portion F^1 . There is thus provided below the piston portion F^1 a clearance space F^3 and above the portion F^1 a clearance space F^4 .

The output control mechanism in the form shown in Figure 1, the operation of which will be described in detail below, is substantially the same as that shown in Figure 4. There are,

however, certain additional features necessary with the two-stage compressor which occur in Figure 4, which will be described below.

G is a housing member formed preferably integrally with the housing member B and serving to provide a number of chambers and controlling means. At the upper end of the member G is a chamber G^1 within which is seated a valve G^2 , which is preferably carried on a threaded shaft G^3 by means of which it may be adjusted up or down. G^4 is a second chamber formed in the member G . G^5 is a hollow valve member slidably mounted within the housing member G and adapted to project into the chambers G^1 and G^4 . It is preferably provided with a laterally extending flange G^6 . G^7 is a spring mounted about the valve G^5 and beneath the flange G^6 and adapted, when free to do so, to hold the valve up in the position shown in Figure 4, so that the valve G^2 is seated in and closes it. G^8 is a lever pivoted within the chamber E at G^9 and extending partially within the housing member G and arranged so that one end may contact the flange G^6 of the valve G^5 . At its other end the lever G^8 is positioned over the rod C^4 which, in the form of the invention shown in Figure 4, is extended upwardly so that it may contact the lever. A pipe G^{10} forms an extension from the pipe C^7 and communicates with the chamber G^4 .

H is a pipe leading from the chamber G^1 to the servo-motor housing H^1 . H^2 is a pipe leading from the servo-motor housing to the pipe E^1 . The pipe H^2 may be provided with a throttle H^3 . Mounted within the servo-motor housing H^1 is a piston H^4 . A spring H^5 serves, when free to do so, to hold the piston in its outer position. H^6 is a by-pass pipe leading from the servo-motor housing to the pipe H^2 . It will be noticed that the pipe H^2 leads from the housing H^1 on one side of the piston and that the pipe H^6 leads from the housing on the opposite side of the piston. H^7 is a valve stem attached to the piston H^4 and carrying a valve member H^8 . H^9 is a clearance chamber which may be in communication with the clearance space F^3 through a port H^{10} , which port is controlled by the valve H^8 .

It will be realized that whereas I have herewith shown and described a practical operative device, nevertheless many changes might be made in the size, shape, number and disposition of parts without departing from the spirit of my invention and I wish, therefore, that my showing be taken as in a sense diagrammatic.

The use and operation of the two forms of the device are substantially the same. In each case the output control is effective to cause the compressor to operate under certain desired pressure conditions in some part of the system, and the output control is, therefore, an automatic, adjustable means to insure such regulation. This control may, for example, in the case of a refrigerating system, be responsive to the pressures in the low pressure section, the pressures existing in the intake manifold, which in the particular case of the compressor, showing herein described, would be the crank drives, where it would be desirable to deliver varying quantities within certain pressure limits. In such a case, the control would be made responsive to the pressures existing in the discharge manifold instead of in the suction. The apparatus may be adjusted by adjusting the pressure on the spring D^{13} . In the case of the form shown in Figure 4, the position of the valve G^2 may be ad-

justed to cause the control assembly, designated generally by H, to operate in the proper phase relationship with the control apparatus designated generally as D. The maximum volumetric 5 output of the compressor occurs when there is the smallest possible dead space or clearance within the cylinder. In this condition piston C is fully lowered so that it completely fills the cylinder B³ and thus this cylinder is not available as additional clearance space, and the ports B⁵, B⁶ and B⁷ are also closed by the piston C so that the additional clearance spaces which they control 10 are also closed.

In order to change the output, the clearance is 15 changed. This is accomplished by moving the piston C back and forth under a control which is co-ordinated with the suction pressure, or some other factor, so that the movement of the piston C is automatically varied in co-ordination with 20 variations in the suction pressure or discharge pressure, but remains locked against cyclic variations in cylinder pressure.

With the parts in the positions shown in Figure 1, the piston C has been somewhat withdrawn 25 in the cylinder B³ so that a portion of that cylinder is open and thus furnishes additional clearance. The port B⁵ is also partly open, and the clearance space B⁸ is thus available as it is connected by the open port with the working space in 30 the cylinder.

The pipe C⁷ is supplied with liquid under pressure from any suitable source. It may be from a pump, which is not shown. From this pipe the fluid under pressure is supplied to the working 35 spaces C² and C³, respectively, below and above the piston C¹, and so long as the pressure remains thus equal within these two spaces, the pistons C and C¹ will not be moved by pressure variations within the cylinder A.

40 The pipe C⁷ is divided into two branches C⁸ and C¹², connecting with the spaces C² and C³, in the order named. In these branches are the throttling valves C⁹ and C¹⁰, which permit a small, regulated flow of liquid, but upon any demand 45 for increased flow, will produce decided pressure differentials.

The space E within the upper part of the housing B is connected by means of the pipe E¹ to the intake of the compressor which may, for 50 convenience sake, be in the enclosed crank space of the compressor and E is thus under the suction pressure of the compressor and as that pressure varies, the pressure within the space E will vary. The pressure within the space E is effective 55 upon the member D¹⁷ to compress it against the spring D¹⁸, or to permit it to expand under the influence of the spring D¹⁸ depending upon whether the pressure within the chamber E rises or falls. With an increase of pressure the member D¹⁷ is partially collapsed and with a decrease 60 of pressure it expands. The space D²², defined by the member D¹⁷, is open to some reference pressure, for example, the atmosphere, against which variations in pressure, either positive or negative, in the chamber E, will be effective to cause 65 movement of the member D¹⁷.

When the pressure within the chamber E rises, due to a rising suction pressure, the member D¹⁷ is compressed and carries with it the lever D¹³, 70 thus lifting the slide valve D⁵ and bringing the port D⁶ in register with the port D⁹ and thus opening the pipe D so that the fluid under pressure may flow from the space C², through the pipe D, the ports D⁹ and D⁶ and the hollow interior of the valve D⁵, into the space E, and

from there it may discharge through the pipe E¹. Since the ports D⁶ and D⁹ are larger than the orifice of the throttling member C⁹, in the pipe C⁸, the pressure in the space C² drops and the piston C¹ will respond to a pressure difference 5 existing between space C³ and C² and upon an increase in pressure in C³ over C² will move downward. This pressure difference between C² and C³ is caused by the registering of the ports D⁶ and D⁹, which provide a free passage from the 10 space C² through the pipe D into the chamber E, and by the out-of register or closed position of the ports D¹⁰ and D⁷, which prevent free escape of liquid from the space C³. The liquid supply from the pipe C⁷ through the pipe C⁸ and C¹², 15 of course, continues, but due to the throttle C⁹, sufficient liquid cannot move into C² to maintain pressure there, against the free exit established through D, D⁶ and D⁹. However, liquid can pass through C¹² and the throttle C¹⁰ to build up pressure in C³, since the exit D⁸ is closed. This overbalanced pressure in C³ as against C² causes the 20 piston C¹ to move downward.

It is to be noted that the throttling valves C⁹ and C¹⁰ serve practically as a hydraulic lock 25 under a condition when both exits D and D⁸ are blocked. In other words, the piston C¹ will not move any measurable amount against rapid fluctuation of pressure against its lower end due to the damping or throttling effect existing in 30 the circuit connecting the spaces C² and C³. As the pistons C and C¹ move downward, the clearance space within the cylinder B³ is reduced and the port B⁵ is also covered by the piston C and thus the additional clearance space B⁸ is cut 35 off from the working space of the compressor. The piston C¹ carries with it the rod C⁴ which moves the lever D¹¹ to raise the cut-off valve D⁸ and as this valve is raised the port D⁹ is moved 40 out of register with the port D⁶ and the passage through the pipe D is thus closed, and further discharge of fluid under pressure through the pipe D is cut off and since pressure can no longer escape from the working space C², a balance 45 between the pressure in the space C² and that in the space C³ is at once established and equilibrium is established, with the double piston C, C¹ in a new position.

As a result of this new position the clearance 50 space in the compressor has been reduced and the output of the compressor is thus increased.

Upon the reduction of the suction pressure, the pressure within the chamber E is correspondingly reduced and the spring D¹⁸ is again able to expand and to move the member D¹⁷ inward. 55 This causes the lever D¹³ to swing inwardly about its pivot D¹⁴ and to move the slide valve D⁵, and the port D⁷ is brought into register with the port D¹⁰ and thus the way is opened for the discharge 60 of the pressure fluid from the working space C³ through the pipe D³, the ports D¹⁰ and D⁷ and the interior of the valve D⁵ into the chamber E. At this time no discharge can occur through the pipe D and thus the pressure in the working space C² is effective to raise the double piston C¹, C, 65 since a free passage has been established in D³ and liquid is restrained by the throttle C¹⁰ from maintaining pressure in the space C³. As the piston C¹ moves upward it, of course, raises the rod C⁴ and rotates the lever D¹¹ to pull downward the valve D⁸ which tends to move the port D¹⁰ out of register with the port D⁷ and thus 70 either reduces or entirely cuts off the discharge of pressure fluid from the working space C³ 75

through the pipe D³, so that a position of equilibrium is again established for the piston C¹. By adjusting the screw D²⁰ the load on the spring D¹⁸ may be set to control the action of the output 5 control and particularly so as to control the time of opening of the ports into the various additional clearance spaces, such as the spaces B⁸, B⁹ and B¹⁰.

The operation of the parts of the output control which appear also in the two-stage compressor of Figure 4, is the same as the operation just described for them in connection with Figure 1. The connection of the additional clearance spaces to the cylinder is the same. Thus the cylinder 15 B³ is connected with the upper end of the cylinder F⁴ in the same manner in the two figures and similarly the ports and the control of the ports B⁵, B⁶ and B⁷ is the same in the structures shown in the two figures. However, certain additional 20 features are necessary in the multiple stage compressor. Thus the rod C⁴, which is attached to the piston C¹ is preferably made longer in the form shown in Figure 4, in order that it may contact the lever G⁸. When this lever is contacted 25 by the rod C⁴ it is shorter and is depressed against the flange G⁶ and moves it downward so as to unseat the valve G² and to open a passage to permit discharge of the pressure agent from the chamber G¹ through the pipe H. Thus pressure 30 is fed from the chamber G¹ to the servo-motor within the housing H¹. With the valve G² unseated, the quantity of pressure fluid which is discharged through the pipe H to the servo-motor is greater than that which can escape through the 35 throttle H³ of the pipe H² and thus the pressure of the liquid on the servo-motor piston H⁴ is sufficient to overcome the force of the spring H⁵ and thus to move the piston back against the spring and so to unseat the valve H⁶ and to open the 40 port H¹⁰, and provide a path to the additional clearance space H⁹, which is added to the second stage of the compressor.

By turning the screw G³ upon which the valve G² is mounted, the member G⁶ can be raised or 45 lowered against the spring G⁷ and thus the time when the lever G⁸ will contact the member G⁶ may be varied, so that the time of the opening of the additional clearance space H⁹ may be established at any desired pressure, and correlated to 50 the conditions of the first stage. It will be understood that the pressure fluid which passes from the chamber G¹ is supplied through the pipe C⁷ and the extension C¹⁰ and flows first into the chamber G⁴ and thence, when free to do so, 55 through the hollow interior of the spring-supported valve seat G⁵.

There might be provided for the second stage of the compressor not merely a single additional clearance space H⁹, but any desired number of 60 additional clearance spaces.

In the form shown and described, the compressor is adapted for use in a refrigerating system where the control will be responsive to changes occurring on the intake side of the compressor, 65 which is also usually the low pressure side of the heat interchanger, and hence responsive to the heat load upon the system. The system obviously can be used in many other ways, and another such use, which would involve a somewhat different arrangement, wherein the control would be responsive to the discharge pressures, would be that of compressed air power tool service, where varying 70 volumes of air are needed within certain pressure limits. It might also be used for liquefaction of gases, wherein the control would be responsive to 75

the out-put side of the apparatus instead of the in-put, as shown in the preferred form.
I claim:

1. In a compressor, a compression chamber, a clearance chamber adjustable as to size and in communication with the compression chamber, additional fixed clearance chambers, piston valve means for varying the first named chamber and for bringing the second named chambers into communication successively with the compression 10 chamber.

2. In a compressor having a variable clearance chamber, pressure-responsive fluid operated means for adjusting said clearance chamber, and means for holding said adjustment locked, said pressure-responsive adjusting means being in communication with and affected by variations in a pressure within the compressor system.

3. In a variable clearance compressor, means for varying the clearance, including an automatic pressure-responsive fluid control, constant throttling and co-operative free passage valve elements adapted to control the flow of fluid in the control means, said pressure-responsive control means being in communication with and affected by variations in a pressure within the compressor system.

4. In a multi-stage compressor, a plurality of compression chambers, a plurality of clearance chambers associated with the compression chambers, controllable valve means for connecting the clearance chambers with the compression chambers and a pressure-responsive, automatic, unitary control for said valve means, said pressure-responsive control means being in communication with and affected by variations in a pressure within the compressor system.

5. In a reciprocating gas compressor of fixed working stroke, automatic means for varying the clearance volume responsive to pressure changes outside the compression chamber, and automatic means for holding any given amount of clearance volume constant against pressure changes occurring within the compression chamber, said pressure-responsive clearance varying means being in communication with and affected by variations in a pressure within the compressor system.

6. In combination in a compressor, a main cylinder having a clearance space and a piston mounted to reciprocate therein, and an output control for said compressor, comprising a plurality of additional clearance space chambers, one of said chambers being directly in communication with said main cylinder, and ports adapted to bring the said additional clearances into communication with the main cylinder, a piston mounted in said first mentioned clearance chamber, and arranged to move to vary the effective size of said chamber, and means responsive to the suction of the compressor, for moving said piston to control said additional clearance spaces.

7. In combination in a compressor, a main cylinder having a clearance space and a piston mounted to reciprocate therein, and an output control for said compressor, comprising a plurality of additional clearance space chambers, one of said chambers being directly in communication with said main cylinder, and ports adapted to bring the said additional clearances into communication with the main cylinder, a piston mounted in said first mentioned clearance chamber and arranged to move to vary the effective size of said chamber, and to control the opening of said ports, and means responsive to the suction of the compressor, for moving said piston to control said additional clearance spaces.

8. In combination in a compressor, a main cylinder having a clearance space and a piston mounted to reciprocate therein, and an output control for said compressor, comprising a plurality of additional clearance space chambers, one of said chambers being directly in communication with said main cylinder, and ports in communication with said chamber and adapted to bring the said additional clearances into communication with the main cylinder, a piston mounted in said first mentioned clearance chamber and arranged to move to control the opening of said ports, and means responsive to the suction of the compressor, for moving said piston to control said additional clearance spaces. 15
9. In combination in a compressor, a main cylinder having a clearance space and a piston mounted to reciprocate therein, and an adjustable, automatic output control for said compressor, comprising a plurality of additional clearance space chambers, one of said chambers being directly in communication with said main cylinder, and ports in communication with said chamber and adapted to bring the said additional clearances into communication with the main cylinder, a piston mounted in said first mentioned clearance chamber and arranged to move to control the opening of said ports, and means, responsive to the suction of the compressor, for automatically moving said piston to control said additional clearance spaces. 20
10. In combination in a compressor, a main cylinder having a clearance space, and a piston, an auxiliary cylinder adapted to furnish an additional clearance space for said main cylinder, a piston in said auxiliary cylinder mounted to be moved to adjust the effective clearance within said auxiliary cylinder, and a pressure-responsive apparatus adapted to control and to vary the position of said auxiliary piston, said pressure-responsive apparatus means being in communication with and affected by variations in a pressure within the compressor system. 25
11. In combination in a compressor, a main cylinder having a clearance space, and a piston, an auxiliary cylinder adapted to furnish an additional clearance space for said main cylinder, a piston in said auxiliary cylinder mounted to be moved to adjust the effective clearance within said auxiliary cylinder, and a pressure-responsive apparatus adapted to control and to vary the position of said auxiliary piston, said pressure-responsive apparatus being in communication with and affected by variations in the suction pressure of said compressor. 30
12. In combination in a compressor, a main cylinder having a clearance space, and a piston, an auxiliary cylinder adapted to furnish an additional clearance space for said main cylinder, a piston in said auxiliary cylinder, mounted to be moved to adjust the effective clearance within said auxiliary cylinder, and a plurality of additional clearance spaces, ports in the walls of said auxiliary cylinder and communicating with said additional clearance spaces, said auxiliary piston in its movement controlling the opening of said ports, and a pressure-responsive apparatus adapted to control and to vary the position of said auxiliary piston, said pressure-responsive apparatus means being in communication with and affected by variations in a pressure within the compressor system. 35
13. In combination in a compressor, a main cylinder having a clearance space, and a piston, an auxiliary cylinder in free communication with said main cylinder and adapted to furnish an additional clearance space therefor, a piston in said auxiliary cylinder mounted to be moved to adjust the effective clearance within said auxiliary cylinder, and a plurality of additional clearance spaces, ports in the walls of said auxiliary cylinder and communicating with said additional clearance spaces, said auxiliary piston in its movement controlling the opening of said ports, and a pressure-responsive apparatus adapted to control and to vary the position of said auxiliary piston, said pressure-responsive apparatus means being in communication with and affected by variations in a pressure within the compressor system. 40
14. In combination in a compressor, a main cylinder having a clearance space, and a piston, an auxiliary cylinder adapted to furnish an additional clearance space for said main cylinder, a piston in said auxiliary cylinder mounted to be moved to adjust the effective clearance within said auxiliary cylinder, and a plurality of additional clearance spaces, ports in the walls of said auxiliary cylinder and connecting said additional clearance spaces with said cylinder, said auxiliary piston in its movement controlling the opening of said ports, and a pressure-responsive apparatus adapted to control and to vary the position of said auxiliary piston, said pressure-responsive apparatus means being in communication with and affected by variations in a pressure within the compressor system. 45
15. In combination in a compressor, a main cylinder having a clearance space, and a piston, an auxiliary cylinder adapted to furnish an additional clearance space for said main cylinder, a piston in said auxiliary cylinder mounted to be moved to adjust the effective clearance within said auxiliary cylinder, and a plurality of additional clearance spaces, ports in the side of said auxiliary cylinder connecting said additional clearance spaces with said cylinder, said auxiliary piston in its movement controlling the effective size of said auxiliary cylinder and the opening of said ports, and a pressure-responsive apparatus adapted to control and to vary the position of said auxiliary piston, said pressure-responsive apparatus means being in communication with and affected by variations in a pressure within the compressor system. 50
16. In combination in a compressor, a main cylinder having a clearance space, and a piston, an auxiliary cylinder adapted to furnish an additional clearance space for said main cylinder, a piston in said auxiliary cylinder mounted to be moved to adjust the effective clearance within said auxiliary cylinder, and a plurality of additional clearance spaces, ports in the side of said auxiliary cylinder connecting said additional clearance spaces with said cylinder, said auxiliary piston in its movement controlling the opening of said ports, and a pressure-responsive apparatus adapted to control the position of said auxiliary piston, said pressure-responsive apparatus being in communication with and affected by variations in the suction pressure of said compressor. 55
17. In combination in a compressor, a main cylinder having a clearance space, and a piston, an auxiliary cylinder in free communication with said main cylinder and adapted to furnish an additional clearance space therefor, a piston in said auxiliary cylinder mounted to be moved to adjust the effective clearance within said auxiliary cylinder, and a plurality of additional clearance spaces, ports in the walls of said auxiliary cylinder and communicating with said additional clearance spaces, said auxiliary piston in its movement controlling the opening of said ports, and a pressure-responsive apparatus adapted to control and to vary the position of said auxiliary piston, said pressure-responsive apparatus means being in communication with and affected by variations in a pressure within the compressor system. 60

clearance spaces, ports in the side of said auxiliary cylinder, connecting said additional clearance spaces with said cylinder, said auxiliary piston in its movement controlling the opening 5 of said ports, and a pressure-responsive apparatus adapted to control the position of said auxiliary piston, said pressure-responsive apparatus being in communication with and affected by variations in the suction pressure of said compressor.

18. In combination in a compressor, a main cylinder having a clearance space, and a piston, an auxiliary cylinder in communication with said main cylinder and adapted to furnish an 15 additional clearance space therefor, a piston in said auxiliary cylinder mounted to be moved to adjust the effective clearance within said auxiliary cylinder, and a plurality of additional clearance spaces, ports in the side of said auxiliary

cylinder, connecting said additional clearance spaces with said cylinder, said auxiliary piston in its movement controlling the opening of said ports, and a pressure-responsive apparatus adapted to control the position of said auxiliary piston, said pressure-responsive apparatus being in communication with and affected by variations in the suction pressure of said compressor.

5

19. In a compressor, a compression chamber, a variable clearance chamber in communication 10 with the compression chamber, additional fixed clearance chambers, piston valve means for varying the first named chamber and for bringing the second named chambers into communication successively with the compression chamber, and means for holding said piston valve stationary against cyclic pressure variations in the compression chamber.
